UNITED STATES PATENT OFFICE.

WILLIAM G. G. WEIDINGER, OF CHICAGO, ILLINOIS, ASSIGNOR OF ONE-THIRD TO EDA WEIDINGER AND ONE-THIRD TO EMMA WEIDINGER, BOTH OF CHICAGO, ILLINOIS.

PROPELLER-SCREW.

1,123,152.

Specification of Letters Patent. Patented Dec. 29, 1914.

Application filed October 28, 1912. Serial No. 728,082.

To all whom it may concern:

Be it known that I, WILLIAM G. G. WEIDINGER, a citizen of the United States, residing at the city of Chicago, in the county of Cook and State of Illinois, have invented 5 certain new and useful Improvements in Propeller-Screws, of which the following is a specification.

My invention relates to propeller screws 10 for marine and aerial use.

The object is to bring about a more economical application of power applied, and to increase the efficiency of the propeller by giving it a greater grip on the fluid medium in which it operates, thereby diminishing 15 the slip and the tendency to churn, which are characteristic of the ordinary propeller.

The principles of my invention are illustrated 20 in the drawings, in which—

Figure 1 represents a side view of my improved device; Figs. 2, 3 and 4 represent respectively front, rear and perspective views of the same.

25 Further describing my invention with reference to the drawings: 1 is a shaft attached to a source of power; 2 is a hub threaded on the shaft and secured against rotation by the key 3, further security of 30 attachment being made by the nut 4. Secured to the hub and projecting therefrom at a suitable angle are the propeller blades 5. These are extended outwardly and back- 35 wardly at any desired pitch, which, how- ever, will vary according to the service to be performed. The outer peripheral edges of the blades are substantially in a straight line from front to rear, and extended there- 40 from is a flange or fin 6. It may be integral 45 with the propeller blade as preferred, and extends from the point *a* to the front edge at *b*. This flange should be transversely curved throughout its length, and the cur- 45 vature at any point may be in the arc of a circle whose center is the corresponding point on the longitudinal axis of the screw and whose periphery is described by the revolution of those points on the outer edge

of the screw from which the said flange 50 springs and which are cut by a line at right angles to the said point on the longitudinal axis. It will be seen that when the flange turns with the screw, the edge *b* cuts the water, and the body portion thereof follows through without resistance. At the same 55 time the propeller blade, by its rotation, forces the water backwardly and outwardly. The outward flow of the water is met by the flange, thereby increasing the resistance and the reaction of the water against the screw, 60 resulting in greater efficiency which, at the same time, may be obtained with slower rotation and little loss of power.

I claim:

1. A propeller screw comprising a hub, 65 blades extended outwardly therefrom and having their peripheral edges in a substan- tially straight line, and flanges springing 70 from the peripheral edges of said blades ex- tended forwardly in a curve substantially corresponding to the arc of their normal revolution.

2. A propeller screw comprising a hub, 75 blades extended outwardly therefrom, and flanges springing from the peripheral edges of said blades extended forwardly there- 80 from and substantially conformed in cross section at each point throughout their length to the arc of revolution of the correspond- ing point at which the said flanges spring 85 from the said blade.

3. A propeller screw comprising a hub, 85 blades extended outwardly therefrom and having their peripheral edges in a substan- tially straight line and flanges spring- 90 ing from the peripheral edges of said blades extended forwardly therefrom and substan- tially conformed in cross section at each point throughout their length to the arc of revolution of the corresponding point at 95 which the said flanges spring from the said blades.

4. A propeller screw comprising a hub, 95 blades extended outwardly therefrom and flanges springing from the peripheral edges of said blades and extended forwardly there-

from, said flanges having a contour substantially corresponding to a section of a figure generated by the revolution of the line of the peripheral edges of said blades about their axis.

In witness whereof, I have hereto subscribed by name this 23rd day of October

1912, in the presence of two subscribing witnesses.

WILLIAM G. G. WEIDINGER.
